WALTER N. SHERWOOD, OF NORTH HOOSICK, NEW YORK

PAPER-PULP BEATER

Application filed October 13, 1928. Serial No. 312,363.

My invention relates to a method of and apparatus for beating pulp. As is well known, paper pulp beaters embody generally a vat or tub, within which is arranged a revolving beating roll or drum. This roll or drum is equipped with radial blades, extending longitudinally of the same, for affording buckets. A bed is arranged beneath the beating roll or drum and is provided with spaced blades forming buckets, the two sets of blades coacting to beat the pulp. Arranged at the rear of the drum is a backfall. The pulp is beaten by the drum, and is pushed over the backfall, and circulates through the vat or tub. In the operation of these prior art beaters, the beating roll or drum must be driven at a relatively low speed, such as about 1400 to 1750 peripheral feet per minute. Attempts have been made to drive these beating rolls at a higher speed, but it is found that the rolls will not then push the pulp over the backfall, but the pulp will travel around with the roll, and the roll will wallow in the pulp. As far as I am aware, no one has succeeded in constructing a paper pulp beater, wherein the beating roll is driven at a high speed, namely at a speed of about 2500 to 3500 peripheral feet per minute, more or less. The work that the beater will do naturally depends upon the speed at which the beating roll can be successfully driven, and although this fact has heretofore been recognized, no one, as far as I am aware, has succeeded in producing a high speed paper pulp beater, as above indicated. Further, in the prior art paper pulp beaters, the circulation or travel of the pulp through the vat or tub is not entirely satisfactory. The travel of the pulp is far from uniform portions of the pulp frequently remaining stationary, necessitating this portion of the pulp being individually worked. To meet this condition, it has been proposed to place paddle wheels in the vats.

In accordance with my invention, I provide a paper pulp beater embodying a vat or tub having a channel or passage in which the pulp circulates, in a manner to be described. A beating roll or drum is located within the channel of the vat. This beating roll is de-

signed to be driven at a high speed, namely at a speed far in excess to any speed heretofore contemplated in the art. By high speed of this character, I mean a speed of from about 2500 to 3500 peripheral feet per minute. This is found to be the effective high speed limits when a high backfall is used, that is a backfall extending above the axis of rotation of the backfall. When the backfall is lowered, the effective high speed limits will be 2000 to 3500 peripheral feet per minute. In order to obtain satisfactory results by the use of the high speed beating roll, I have found it necessary to increase the number of blades carried by the roll, far in excess of that contemplated by the prior art. In the prior art beater, the blades upon the drum are ordinarily arranged about $2\frac{1}{2}$ " to $3\frac{1}{4}$ " apart from center to center. My blades are arranged not farther apart than one inch, and I also form my blades much thinner. The result is that I employ from two to three times as many blades upon the beating roll, as has heretofore been the practice, and the pockets between the blades on my beating roll are about one inch in width and about one inch deep. By rapidly rotating my beating roll, as explained, an entirely different mode of operation is produced in the handling of the stock. Not only is the stock subjected to a much greater beating action, but it is propelled by the roll in an entirely different manner. In the low speed rotating pulp beaters, the pulp is simply pushed over the backfall, by the beating roll, and as stated, if it is attempted to rotate the roll, at a high speed, the pushing action is impaired, and the roll simply wallows in the pulp.

In the operation of my high speed beating roll, the pushing action is not present, but the pulp is violently projected or thrown from the beating roll by centrifugal force. This pulp is thrown over the backfall, upon or into the pulp which is circulating or traveling in a direction at a right angle to the movement of the projected pulp. The circulation of the pulp at the rear of the backfall is effected by means of an inclination. By rapidly throwing or projecting the pulp from the beater roll, upon or into the pulp

circulating at a right angle thereto, a cross current action is obtained, effecting a thorough mixing of the same.

By virtue of the small or shallow buckets 5 or pockets upon the beating roll, I obtain a squashing roll or mix at the beating roll and bed plate. By rapidly ejecting or throwing the pulp from the beating roll by means of centrifugal force, I obtain a hydration by 10 forced mixing. By throwing the mix from the mixing roll across the direction of circulation of the mix, in the vat, at the rear of the roll, I obtain a cross current mix. By the peculiar construction of the channels or passages in the vat, I obtain cross section mixing, compression mixing, expansion mixing, strata breaking corner mixing, and gravity sag mixing.

In the accompanying drawings, forming 20 a part of this specification, and in which like numerals are employed to designate like parts throughout the same,

Figure 1 is a side elevation of a paper pulp beater embodying my invention,

25 Figure 2 is a plan view of the same,

Figure 3 is a longitudinal section taken on line 3—3 of Figure 1,

Figure 4 is a transverse section taken on line 4—4 of Figure 1,

30 Figure 5 is a similar view taken on line 5—5 of Figure 1,

Figure 6 is a fragmentary side elevation of the beating roll or drum,

Figure 7 is a detail fragmentary transverse 35 section through the same,

Figure 8 is a fragmentary central longitudinal section through the drum,

Figure 9 is a plan view of the beating roll bed, and,

40 Figure 10 is a transverse section taken on line 10—10 of Figure 9.

In the drawings, wherein for the purpose of illustration, is shown a preferred embodiment of my invention, the numeral 15 designates a vat or tub, which is preferably elongated, with three of its corners preferably rounded, although the invention is in no sense restricted to this precise shape. Extending generally centrally longitudinally within the 45 vat or tub is a mid-feather 16, and a mid-partition 17 extends parallel with the mid-feather, and is spaced therefrom, affording a lighter beam chamber 18. The mid-feather 16, instead of extending straight throughout its entire length, as is ordinarily the case, is cut between its ends and its forward portion 19 is transversely inclined for a distance about 30° from the rear portion of the mid-feather. The forward portion of the mid-feather intersects with the mid-partition 17, and a curved wall 20 is secured to the ends of these parts, as shown, for producing a contracted portion in the channel of the vat, for a purpose to be described.

65 The numeral 21 designates a high speed

beating roll or drum, which is shown in detail in Figures 6, 7, and 8. This roll is preferably heavy, so that it will rotate smoothly at a high speed, and for this purpose it may be formed of a pair of roll heads 22, which are rigidly mounted upon a shaft 23. A wooden ring or filler 24 is securely clamped between the ends of the roll heads. The roll heads 22 are provided upon their peripheries with spaced radial lugs 25, receiving therebetween metal fly bars 26, having snug frictional engagement therewith. These metal fly bars are radially disposed and are provided in their ends with notches 27 receiving metal rings 28, which serve to securely hold them in place upon the roll. The fly bars 26 are constructed much thinner than the ordinary fly bars, and may be only half the thickness of the ordinary fly bars. I prefer to space the fly bars 26 at about 1 1/4" from center to center, thereby providing a bucket or pocket one inch wide. Arranged between the fly bars 26 are fly bar fillers 29, preferably formed of wooden strips or about 1/8" to 1/4" thick. These fly bar fillers fit tightly between the fly bars 26 and are held in place by frictional engagement but in addition to this they may be nailed to the filler ring 24. The depth of the bucket is preferably an inch, and when the fly bars wear down, the depth of the bucket may be restored by removing one or more of the fillers. The buckets or pockets are ordinarily maintained at about a square inch in cross section, which is about one-fourth to one-sixth of the size of the ordinary bucket. From various tests which I have made, I find that the small size of the buckets is an important factor in the use of a high speed beater. This reduces the volume of stock which the beater roll handles at a given speed, and enables the beater roll to successfully handle the proper volume of stock when driven at a high speed. The beater roll is rigidly mounted upon the transverse drive shaft 23, which is journaled in 100 bearings 31, mounted upon lighter beams 32. By reducing the size of the beater roll, the size of the drive shaft may also be reduced, and the bearings maintained properly lubricated. The lighter beams 32 are provided at their forward ends with openings 33, which are not screw-threaded, and slidably receive the lower screw-threaded ends of vertical adjusting shafts 34, but have no screw-threaded engagement therewith. These screw-threaded ends carry nuts 35, held against turning movement by engagement with the sides of the lighter beams. The upper ends of these adjusting shafts pass through openings in a transverse stationary timber or beam 36, and horizontal bevel gears 37 are rigidly attached to these shafts. These bevel gears are engaged by vertical bevel gears 39, mounted upon a transverse horizontal shaft 40. The shaft 40 is journaled 115

through openings in angle irons 41 secured in the transverse timber. The shaft 40 is equipped with a hand wheel 42 at one end by means of which it may be turned. The 5 opposite ends of the lighter beams rest upon cam elements 43, which are rigidly secured to a rock shaft 44, and have faces 45, arranged at varying distances from the shaft. The rock shaft 44 is turned by means of a lever 46. By turning the rock shaft, it is obvious that the lighter beams may be quickly raised, and the beater drum elevated, in the event that an obstruction should pass between the beater drum and the bed. Further, by manipulation of the lever 46, the beater roll 10 may be quickly raised and allowed to run idle after the beating operation has been completed and it is desired to dump the vat. Further, it provides the means whereby the 15 beater roll may be quickly adjusted to different elevations particularly when coarse stock is first being treated. The cam elements are clamped to the rock shaft 44 by set screws, and these cam elements may be 20 turned upon the rock shaft and reset, which is desirable when the forward end of the lighter beams have been permanently lowered, to compensate for the wear upon the fly-bars.

The numeral 47 designates a backfall, arranged near and at the rear of the beating roll, and having an inclined front face or surface 48. The front face 48 has its lower portion curved and disposed concentric to the beating roll in close relation thereto. 30 The upper portion of the front face 48 is disposed at a tangent to the beating roll and is inclined upwardly toward its top from the beating roll, to provide a suitable space whereby the pulp may be projected from the beating roll into the air and thrown over the backfall due to the action of centrifugal force. This backfall is tall and preferably extends above the axis of rotation of the roll. The pulp circulating passage has a uniform 40 depth throughout its length. This backfall has an opening 50, within which the rock shaft 44 is rotatably mounted. The numeral 51 designates a bed, arranged beneath the beating roll and in advance of the backfall 47. This bed embodies sets of spaced shears 52 and 53. Each shear is bent into transversely inclined portions 54. The rear set of shears 53 are reversed with respect to the forward set of shears 52, and a straight bar 55 or strip 55, separates the two sets of shears. The inclined portions 54 of the shears produce a cutting action upon the pulp, and this action is reversed as the pulp is passed from one set of shears to the other. While it is 55 preferred to use the center bar 55, yet the invention is in no sense restricted to the use of the same. The shears in each set, are placed relatively close together, and I have found that satisfactory results are obtainable 60 by spacing them for a distance of $\frac{1}{4}$ ", al-

though this distance may be varied. The entire bed is transversely curved to form of the curvature of the beater roll.

These shears are suitably rigidly clamped into a frame or bed plate box 56, which in turn is suitably mounted in the vat or tub. The beater roll is adjusted vertically by means of the hand wheel 42, so that its fly bars travel close to the shears of the bed, for instance $1/100''$, although the distance is increased when the pulp is not to be beaten so fine.

Arranged near and in advance of the bed are spaced rollers 57, disposed in an inclined group, which leads up to the bed. 80 These rolls serve to effectively feed the pulp to the bed, and also permit of the separation out of foreign solid particles, which fall between the rolls.

The backfall 47 has its rear face 57 vertical, and this face is continued by a partition 58. These parts, with the mid-partition 17, provide a channel 59 in the vat. The channel is relatively wide, so that a large capacity is provided for the high speed beater roll, and the width of the channel varies depending upon the size of the beater roll. The channel embodies a rear transverse channel portion 60, which has its longitudinal axis at substantially a right angle to the direction of rotation of the beating roll. Arranged at the closed end of the transverse channel section 60 is an incline 61, which extends from a point near the top of the backfall 47 to the bottom of the channel section 60, said channel section having a depth for the full depth of the channel. The incline 61 has a width of about one-half to one-third of the length of the beating roll. At the corners of the channel 59, I provide inclined blocks, 90 banks, or strata breakers 62, the purpose of which is to work the pulp or stock at the bottom, at the corners of the channel, and effect a mixing of the strata, loosening the same up, and preventing portions of the 95 stock remaining stationary at the corners. These members effect, in substance, a vertical mixing of the pulp, while it is traveling longitudinally. The wall 20 together with the mid-feather portion 19, produce a restricted 100 compression mixing channel section 63, and this restricted channel section terminates at the point 64, and from this point, the channel is widened producing an expansion mixing channel section 65.

The numeral 66 designates a combined guard and guide, which is attached to the mid-feather 16. When the beating roll acts upon the pulp a portion of the same is more readily finely divided, and this finely divided portion rises to the top in the liquid mass and constitutes the light sloppy portion of the mass or pulp. This element 66 has its lower end projecting downwardly to about the elevation of the top of the backfall 47, so that 110

it will dip into the top of the pulp or stock. The lower edge of this member 66 is slightly curved laterally, and the element 66 extends transversely across the major portion of the channel section 60, but is spaced from its rear wall as shown. The element 66 serves to prevent the pulp thrown by centrifugal force from the beating roll from splashing laterally and also serves to collect and guide the light sloppy stock to the outer or rear wall of the channel. This light sloppy stock, containing a greater amount of water than the heavy stock will thus travel principally near the outer wall of the channel, eliminating the necessity of wetting the stock near the outer wall of the channel as is frequently required where the heavy stock travels near the outer wall.

While the invention is in no sense restricted to the particular size of machine shown and described, yet for the purpose of illustration, I will describe the operation of the machine designed to beat from 600 to 700 pounds of pulp. In the operation of a machine for this purpose, the beater roll would have a diameter of about three feet and a similar length. An ordinary old type machine of this size could only handle about one-half of the amount of stock. In operating my machine, the vat or tub is first about one-half filled with water and the stock is fed into the vat, while the beating roll is adjusted to an elevation of $\frac{1}{4}$ " from the bed 51. The beating roll is now rotating, and is turning at about 2500 to 3500 peripheral feet per minute. The pulp is beaten by passing between the beating roll and the bed 51 is carried rearwardly and upwardly by the pockets of the beating roll. The pulp within the pockets by virtue of the high rotation of the beating roll is rapidly thrown or projected rearwardly over the backfall 47 due to the action of centrifugal force upon the same. The pulp is not slowly pushed by the beating roll, as is the ordinary practice, but is rapidly or violently thrown from the beating roll by centrifugal action. This pulp is thrown in the form of sheets rearwardly over the backfall 47, and is traveling at a right angle to the travel or circulation of the pulp in the transverse channel section 60. The pulp has the maximum depth or elevation in the rear channel section 60, and is circulated or pushed forwardly by the incline 61, causing the continuous gradual circulation of the pulp through the channel, and also by the high gravity sag of the mass. As the pulp travels forwardly it enters the contracted channel section 66, and is compressed, whereby its depth is increased, and mixing effected. The pulp upon reaching the point 64, discharges into the widened channel section 66, and a laterally spreading action occurs, in the widened channel section, causing a thorough mixing of pulp by the spreading action, which is

the reverse of the mixing action in the channel section 63, due to compression. The pulp is again passed beneath the beating roll and bed. As the beating operation continues, the beating roll is gradually moved toward the bed, depending upon the fineness to which the pulp is to be beaten. This is accomplished by turning the hand wheel 42. As the pulp is traveling through the channel, and reaches the corners of the same, the inclined blocks or elements 62 serve to elevate the lower portion of the mass, effecting strata agitation or movements. This eliminates any tendency that the pulp might have to slow down or stop at the corners, which frequently occurs in the old style beaters. The element 66 delivers the light sloppy stock at a point near the rear or outer wall of the channel, thereby causing the same to travel generally, near the outer wall of the channel. As the stock traveling near the outer wall of the channel must travel a greater distance than the mid-feather stock, it is desirable to have the light stock traveling outermost, so that it may travel faster and keep up with the heavy stock. In the old type machine, the heavy stock would generally travel adjacent the outer side of the channel and this was one of the causes for the heavy stock tending to slow up or stop. I am, therefore, enabled to obtain a uniform mixing, with a uniform circulation, in combination with the rapid uniform beat of the stock. In the cycle of operation, the major portion of the pulp or stock is circulating in a uniform manner while the rapidly rotating beating roll rapidly discharges or throws the pulp into the high end of the stock, which serves as a mixing pool.

It is to be understood that the form of my invention, herewith shown and described, is to be taken as a preferred example of the same, and that various changes in the shape, size and arrangement of parts, may be resorted to, without departing from the spirit of my invention, or the scope of the subjoined claims.

Having thus described my invention, I claim:—

1. A paper pulp beater, comprising a vat provided with a pulp circulating passage, a pulp beating roll disposed within the passage, a backfall at the rear of the roll, a bed arranged beneath the roll, and spaced rollers disposed in advance of the bed and arranged in an inclined group leading up to the bed, said rollers effecting the easy travel of the stock to the bed and permitting of the separation from the stock of solid bodies.

2. A high speed paper pulp beater comprising a vat having a pulp circulating passage, a beating roll arranged within said passage, a backfall arranged behind the beating roll and having a front face, the upper portion of the face being inclined rearwardly

from the beating roll to provide sufficient space whereby the beating roll may be driven at a sufficiently high speed to cause the pulp carried thereby to be projected into the air from the same by centrifugal force over the backfall, and a guide element extending to the rear of the backfall and arranged to engage with the upper portion of the pulp and serving to guide the light sloppy portion of the pulp to the outer side of the circulating passage, and a bed arranged beneath the beating roll.

3. The method of beating paper pulp in the presence of water, comprising the steps of circulating the mass in a continuous passage, subjecting the pulp to the action of a high speed rotary beating roll driven at a speed of approximately 2500 to 3500 peripheral feet per minute and thereby projecting the pulp thus treated by the action of centrifugal force into the air from the high speed beating roll and causing the same to travel substantially completely across and above the pulp at the rear of the beating roll and collecting such projected pulp, and causing the collected pulp to travel at substantially a right angle to the direction of travel of the on-coming projected pulp for effecting a cross-mix.

30 4. The method of beating paper pulp in the presence of water, comprising the steps of circulating the mass in a continuous passage, subjecting the pulp to the action of a rotary beating roll having a large number of relatively small buckets and driven at a speed of approximately 2500 to 3500 peripheral feet per minute, and thereby projecting the pulp thus treated by the action of centrifugal force into the air from the beating roll and causing the same to travel substantially completely across and above the pulp at the rear of the beating roll and collecting such projected pulp, and causing the collected pulp to travel at substantially a right angle to the direction of travel of the on-coming projected pulp for effecting a cross-mix.

In testimony whereof I affix my signature.
WALTER N. SHERWOOD.
